UNITED STATES PATENT OFFICE.

EDWARD B. ALLEN, OF BRIDGEPORT, CONNECTICUT, ASSIGNOR TO THE SINGER MANUFACTURING COMPANY, A CORPORATION OF NEW JERSEY.

SEWING MACHINE FOR COVERING REINFORCED EYELETS.

Application filed July 3, 1919. Serial No. 308,570.

To all whom it may concern:

Be it known that I, EDWARD B. ALLEN, a citizen of the United States, residing at Bridgeport, in the county of Fairfield and 5 State of Connecticut, have invented certain new and useful Improvements in Sewing Machine for Covering Reenforced Eyelets, of which the following is a specification, reference being had therein to the accompanying drawings.

This invention relates to machines of the buttonhole sewing type and has for a particular object to provide a machine for covering reenforced eyelets in fabric material.

15 In corset manufacture, for example, it is customary to insert rows of metallic eyelets in the corset halves for reception of the usual lacing strings. The appearance of these eyelets is often objected to, particularly on corsets of the more expensive grades, and it is found desirable to cover such eyelets with an attractive overseam of silk or other thread of appropriate color.

20 Buttonhole or eyelet stitching machines, as commonly constructed, are unsuitable for this work as they are provided with a cutter or punch for cutting a hole in the material immediately prior or subsequent to the sewing operation, i. e., while the work is held 25 clamped in the machine. Such a cutter would be likely to strike and damage the metal eyelet and would serve no useful purpose in connection with work of the character contemplated, as the eyelet holes are 30 already formed in the material before it is presented to the machine. To merely omit the usual cutting devices of prior machines would not render them suitable for this work as it will be appreciated that only with great 35 difficulty and with the exercise of painstaking care can work be placed in the machine by hand so that the eyelet to be covered will exactly register with the stitch-forming mechanism. If such registry is not obtained 40 prior to stitching, the sewing needle or needles will strike the metal or other eyelet reinforcing material and will be broken or deflected, thus damaging the machine or 45 ruining the product.

50 A more general object of the invention may therefore be said to be the provision of a machine for covering reenforced eyelets which will not require the exercise of extreme care on the part of the operator in present-

ing the work to the machine, but which will, 55 within limits, automatically take care of work which is not placed by the operator exactly in register with the stitch-forming mechanism.

In buttonhole machines having a work-holder and buttonhole cutter which operate to clamp and cut the work out of sewing position and then move it into sewing position, it is more difficult to secure the exact 60 register of the cut hole with the stitch-forming mechanism than in machines which clamp and cut the work in sewing position. Also, more time is required to move the work-holder into and out of sewing position 65 by the usual gear driven feed-wheel than 70 is required to move the buttonhole cutting mechanism into and out of register with the stitch-forming mechanism by the usual quick acting cutter-shaft.

The invention has for a further object the 75 provision of a machine which will center and cover the reenforced eyelets in a minimum time and with a maximum degree of accuracy.

To the attainment of the above and other 80 objects, as will hereinafter appear, the invention contemplates the provision of a work positioning or registering implement which operates automatically, prior to closure of the work-clamp, to shift inaccurately positioned work to correct position in 85 register with the stitch-forming mechanism. While such an implement may be constructed in a variety of forms and be operated in various ways, I, for convenience, 90 make use of a work positioning pin having a tapering or rounded extremity which, when projected to sewing position and into an inaccurately placed eyelet will, by virtue of its tapering nose, cause said eyelet to 95 be shifted to a position concentric with the axis of said pin and in exact registry with the stitch-forming mechanism. After the eyelet is registered with the stitch-forming mechanism by the pin, the usual work 100 clamps are closed and the pin is withdrawn and retracted to an out-of-the-way position, after which the stitch-forming mechanism is started and the stitches are laid around the eyelet in the usual manner.

105 In the accompanying drawings which illustrate the invention in its preferred embodiment, Fig. 1 is a side elevation of the

machine with the frame in section to show certain features of the internal mechanism. Fig. 2 is a horizontal sectional view through the standard of the machine showing the 5 work-positioning and holding devices in plan. Fig. 3 is a side elevation of the work-positioning or registering mechanism at a period of the cycle just prior to complete closure of the work-clamps. Fig. 4 is a view 10 on an enlarged scale of the work-positioning implement and parts adjacent the stitching point of the machine at a period of the cycle when the clamps are fully closed and the work-positioning implement is about to be withdrawn. Fig. 5 is a perspective view of 15 the work-positioning implement. Fig. 6 is a perspective view of an auxiliary implement preferably used in cooperation with the work-positioning implement shown in Fig. 20 5 to support the eyelet during the shift thereof. Fig. 7 is an elevation of a modified form of work-positioning implement, and Fig. 8 is a plan view of a reenforced eyelet in process of being covered.

25 In the preferred embodiment of the invention, as illustrated, the machine frame comprises the hollow rectangular base 1 from which rises the standard 2 of the bracket-arm 3 terminating in the hollow head 4.

The stitch-forming mechanism of the machine is preferably constructed substantially in accordance with the disclosure of my Patent No. 1,162,207, of November 30, 1915, and 35 comprises an upper eye-pointed needle 5 which is carried by the needle-bar 6 journaled in the head 4 for the usual reciprocating and axial turning movements. The reciprocating movements are derived from the 40 usual pitman 7 and crank-pin 8 at the forward end of the needle-bar actuating shaft 9 extending within and lengthwise of the bracket-arm 3. This shaft carries a bevel gear 9^a which meshes with a companion gear 10 of twice its size fixed to the upper end of the vertical shaft 11 journaled within the standard 2 and at its lower end carrying a bevel gear 12 which meshes with the driving gear 13 on the main or sewing shaft 14 50 journaled within and lengthwise of the hollow base 1.

The needle 5 cooperates with the usual lower stitch-forming instrumentalities including the curved needle 15 carried by the 55 usual rotary turret mounted to turn within the curb 16 about a vertical axis coincident with the axis of the needle-bar 6. During the sewing operation the needle-bar and turret receive simultaneous step-by-step 60 turning movements from the upper and lower sector-gears 17 and 18, respectively. These gears are connected in the usual manner to a vertical shaft 19 to move in unison and are operated from the feed-wheel 20, 65 all as more fully set forth in my said Patent

No. 1,162,207, and in my Patent No. 1,346,- 102, of July 13, 1920.

The work-holder is of the well known travelling type which clamps the work in stitching position and receives longitudinal and lateral components of motion from the feed-wheel of the machine during the sewing operation. While any suitable type of work-holder may be used, I prefer to employ a work-holder constructed substantially 70 in accordance with the disclosure of my Patent No. 1,334,640, March 23, 1920. Such a work-holder comprises a pair of lower clamping plates 21, 21, which are removably mounted on the usual cross slide-plate 22 75 which, in turn, is carried by the longitudinal slide-frame 23.

The lower clamping plates 21 carry the brackets 24 within which are fulcrumed at 80 the rearward ends of the upper clamping arms 26 having at their forward ends the pivotally mounted clamping feet 27 which 85 clamp the work against the plates 21. The clamping feet 27 have opposed semi-circular cutaway portions defining a circular opening 27' for the stitching or covering of an 90 eyelet in a position directly above the usual throat-plate or button 28 carried by the lower needle-supporting turret.

95 It is understood that the feed-wheel has in its upper face two cam-grooves 29 and 30 which operate through the usual lever connections 29' and 30', such as disclosed in my Patent No. 1,039,241 of September 24, 1912, to impart the necessary lateral and longitudinal components of motion to the work-holder, such components being so chosen in the present instance that the work-holder is moved in a substantially circular path. Step-by-step rotary motion is imparted to 100 the feed-wheel through the usual gear connections 31, Fig. 1, with the star-wheel 32 which is driven by the diametrically opposed pins 33 at the lower end of the shaft 11, as more fully disclosed in my said Patent No. 110 1,346,102.

115 The present machine preferably embodies an auxiliary shaft 34 which performs a single rotation prior to sewing, and another auxiliary shaft 35 which performs a single 115 rotation subsequent to sewing. These shafts and the controlling connections therewith are preferably constructed substantially in accordance with the disclosure of my said Patent No. 1,346,102; the first mentioned auxiliary shaft 34 being described as the "cutter shaft" in said application, and being controlled by means of the usual clutch device 34' and clutch controlling lever 34'' pivoted on the machine frame at 34''' for 120 movement toward and away from the clutch device 34'. As the present machine is designed to operate upon work having previously formed and reenforced eyelet holes 125 therein, there is no need for hole cutting 130

mechanism and the shaft 34 and levers 36 and 37 used in my previous machine to cut a hole in the material are used in the present machine for centering or registering the 5 previously formed hole with the stitch-forming mechanism.

The shaft 34 carries the usual cams 38 and 39 which cooperate respectively with the rearward ends of the levers 36 and 37 to rock 10 the latter about their common fulcrum 40 in the travelling fulcrum-block 41 mounted to slide longitudinally of the bed 1 in the usual manner, as disclosed in my Patent No. 1,048,786 of December 31, 1912. The upper 15 lever 36, instead of carrying at its forward end the usual buttonhole cutting knife, is provided in the present instance with a cylindrical pin 42 having a diameter slightly less than that of the reenforced eyelet holes 20 which the machine is adapted to handle. This pin has a tapering extremity which may be rounded as shown at 42^a in Figs. 4 and 5, or conically pointed as shown at 42^b in Fig. 7. Mounted on the lower lever 37 in 25 cooperative relation with the pin 42 is a work-supporting element 43 having an aperture 44 surrounded by an annular work-supporting surface 45 upon which the eyelet *e* rests as the pin 42 is being projected into 30 said eyelet for the purpose of centering it.

The usual cutter-advancing and retracting cam of my prior machines is utilized in the present machine to advance and retract the fulcrum-block 41 to move the work centering 35 implement 42 with a translatory or travelling movement from retracted position remote from the stitch-forming mechanism to an advanced position in register with the stitch-forming mechanism. This cam is des- 40 ignated by the numeral 46 and operates upon the usual follower 47 at the rearward end of the link 48 which is slotted to embrace the shaft 34 and at its forward end is connected at 49, Fig. 2, with the fulcrum-block 41.

The auxiliary shaft 34 also carries the usual clamp-closing cam 50 which lifts the rearward end of the clamp-closing lever 51 fulcrumed at 52 upon a bracket 53 rigidly 50 carried by the standard 2. The forward end of the clamp-closing lever is positioned over the arm 54 which is fixed to one of the alined clamp-closing rock-shafts 55 common to work-holders of the present type; such rock- 55 shafts being connected by the usual fork and pin device 55'. When the lever 54 is depressed, the cams 56 on the rock-shafts 55 are turned so as to depress the clamp-arms 26 and force the clamping feet 27 into grip- 60 ping relation with the work.

The machine is provided with the stop-motion *s* of well known construction and with the usual controlling mechanism for throwing the stop-motion to running position as the shaft 34 is completing its single

rotation. The machine is also provided with mechanism for starting the second auxiliary shaft 35 when the stop-motion operates to stop the machine after the sewing is completed. These various devices are constructed substantially in accordance with the disclosure of my said Patent No. 1,346,102, and as they are not claimed specifically herein further description thereof is believed to be unnecessary.

The machine is also preferably equipped with the thread-cutting mechanism disclosed in my copending application Serial No. 283,603, filed March 19, 1919, and with the finger-release mechanism for tripping the machine into action as disclosed in my said Patent No. 1,334,640. Such devices, however, form no part of the present invention.

In the operation of the present machine, the work is placed under the raised clamping feet 27 by hand; the operator using some judgment in locating the eyelet to be covered approximately centrally over the small round button or needle-throat 28. The machine is then started by pressing down upon the finger release *b* whereupon the shaft 34 is coupled to the source of power for a single rotation and the levers 36 and 37 advanced and closed, thus projecting the pin 42 into the eyelet and exactly registering the latter with the stitch-forming mechanism. It will be understood that if the eyelet is located eccentrically to the button 28 by the operator, the pin 42 will impart a side shift to the eyelet as the pointed nose 42^a of the pin enters the latter. In the usual buttonhole machine it is customary to close the clamps before the cutter-levers are advanced and closed to cut the buttonhole. In the present instance, however, the so-called "cutter levers" are used for a work-shifting purpose and the clamp-closing cam 50 is accordingly retarded upon the shaft 34 so that it will not fully elevate the rear end of the lever 51 to close the clamps until after the levers 36 and 37 have been fully closed to center the work. After the clamps are closed, the levers 36 and 37 are opened and retracted to a position remote from the stitch-forming instrumentalities.

In the present machine the button 28 may be used by the operator as a sight in locating the reenforced eyelet-hole with the necessary degree of approximate accuracy, such button or the relatively small needle-hole 120 therein being plainly visible through the eyelet-hole when the latter is nearly centered. If the eyelet-hole is not located by the operator with a sufficient degree of approximate accuracy, the centering pin will 125 crush one side of the eyelet and will not operate to shift the eyelet laterally to an exact registering position. It would be much more difficult for the operator to center the eyelet-hole by using the raised clamping 130

feet as a sight, as for example in machines which clamp the work out of stitching position, inasmuch as such feet are spaced vertically above the hole and the line of vision of the operator is materially inclined to the vertical. Where, in the present machine the needle-throat or button 28, which is in contact with the under surface of the work, may be used as a sight, no allowance or mental 10 guess need be made by the operator due to the fact that the line of vision is inclined to the vertical. The eyelet-hole is simply placed centrally over and in contact with the button.

15 During the last part of the single rotation of the shaft 34, the stitch-forming mechanism is tripped into action in the usual manner and operates to cover the eyelet *e* in the body fabric as shown in Fig. 8, 20 the upper needle 5 making the depth stitches and the lower needle 15 passing upwardly through the eyelet to form the overedge or covering stitches. The throat-plate 28 is tilted forwardly during the advance of the work-positioning implements 25 42 and 43 to permit the element 43 to occupy a position in register with the stitch-forming mechanism; such tilting throat-plate being an old and common feature of my prior machines, as disclosed for example 30 in my Patent No. 1,162,207.

While I have shown the present invention as embodied in a machine having various features constructed substantially in 35 accordance with the disclosures of my said prior patents and pending applications, it is to be understood that the invention is not limited in its application to machines of a particular type. The important consideration 40 is the provision of means for registering the hole in the material with the stitch-forming mechanism prior to the closure of the work-clamp.

Having thus set forth the nature of the 45 invention, what I claim herein is:—

1. In a sewing machine, in combination, overedge stitch-forming mechanism, a work-holder, means for relatively moving the stitch-forming mechanism and work-holder to sew around and cover an eyelet hole in the material, a travelling pivoted work centering device normally remote from the work-holder, and means for imparting a translatory component of motion to said 50 device to move it into register with the work-holder and a pivotal component of motion to bring it into engagement with the eyelet to shift the latter into register with the stitch-forming mechanism.
- 55 2. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft
- 60 3. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft 75 with controlling means for causing it to perform a single rotation only preparatory to each stitching operation, and means actuated by said shaft for shifting an improperly placed eyelet hole into register with the stitch-forming mechanism.
- 80 4. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft with controlling means for causing it to perform a single rotation only preparatory to each stitching operation, and means actuated by said shaft for centering the eyelet hole relatively to the stitch-forming mechanism.
- 85 5. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft with controlling means for causing it to perform a single rotation only preparatory to each stitching operation, an eyelet centering pin 90 with means for supporting it in an inactive position remote from the stitch-forming mechanism, means actuated by said shaft for advancing said pin into register with the stitch-forming mechanism and projecting it into the eyelet hole in the work to center the latter, and means for closing the work-clamp upon the centered work.
- 95 6. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft with controlling means for causing it to perform a single rotation only preparatory to each stitching operation, a travelling fulcrum block, a lever fulcrumed on said block, an eyelet centering pin carried at the forward end of said lever, a cam on said auxiliary shaft with connections for shifting said fulcrum block to move the pin to sewing position, a second cam on said shaft for 100 tilting said lever to center the eyelet, and a third cam on said shaft with connections for closing the work-clamp upon the centered eyelet.
- 105 7. In a sewing machine, in combination, upper and lower stitch-forming instrumentalities, a sewing shaft with connections for actuating said instrumentalities, an auxiliary shaft with controlling means for causing it to perform a single rotation only preparatory to sewing, a work centering device, and operative connections between said device and said auxiliary shaft.
- 110 8. In work centering mechanism for eyelet covering sewing machines, the combination,

with controlling means for causing it to perform a single rotation only preparatory to each stitching operation, and means actuated by said shaft for shifting an improperly placed eyelet hole into register with the 70 stitch-forming mechanism.

3. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft 75 with controlling means for causing it to perform a single rotation only preparatory to each stitching operation, and means actuated by said shaft for centering the eyelet hole relatively to the stitch-forming mechanism.

4. In a sewing machine, in combination, stitch-forming mechanism, a work-clamp, 85 feeding mechanism for relatively moving the stitch-forming mechanism and work-clamp to sew around and cover a reenforced eyelet hole in the work, an auxiliary shaft with controlling means for causing it to perform a single rotation only preparatory to each stitching operation, an eyelet centering pin 90 with means for supporting it in an inactive position remote from the stitch-forming mechanism, means actuated by said shaft for advancing said pin into register with the stitch-forming mechanism and projecting it into the eyelet hole in the work to center the latter, and means for closing the work-clamp upon the centered work.

5. In a sewing machine, in combination, stitch-forming mechanism, a work-clamp, feeding mechanism for relatively moving the stitch-forming mechanism and work-clamp to sew around and cover a reenforced eyelet hole in the work, an auxiliary shaft with controlling means for causing it to perform a single rotation only preparatory to each stitching operation, a travelling fulcrum block, a lever fulcrumed on said block, 100 an eyelet centering pin carried at the forward end of said lever, a cam on said auxiliary shaft with connections for shifting said fulcrum block to move the pin to sewing position, a second cam on said shaft for 110 tilting said lever to center the eyelet, and a third cam on said shaft with connections for closing the work-clamp upon the centered eyelet.

6. In a sewing machine, in combination, 120 upper and lower stitch-forming instrumentalities, a sewing shaft with connections for actuating said instrumentalities, an auxiliary shaft with controlling means for causing it to perform a single rotation only preparatory to sewing, a work centering device, and operative connections between said device and said auxiliary shaft.

7. In work centering mechanism for eyelet covering sewing machines, the combination,

tion with a pointed and endwise movable eyelet centering pin of an apertured element adapted to receive said pin and to support the eyelet while it is being centered.

5 8. In work centering mechanism for eyelet covering sewing machines, in combination, a pointed and endwise movable eyelet centering pin, means for supporting said eyelet during entry by said pin, a lever carrying said pin, a travelling fulcrum block for said lever, an actuating shaft and means carried by said shaft for shifting said fulcrum block and for tilting said lever.

10 9. In work centering mechanism for eyelet covering sewing machines, in combination, a pointed and endwise movable eyelet centering pin, an element for supporting

said eyelet during entry by said pin, a pair of levers respectively carrying said pin and element, an actuating shaft, and means carried by said shaft for tilting said levers. 20

10 10. In work centering mechanism for eyelet covering sewing machines, in combination, a pointed and endwise movable eyelet centering pin, an element for supporting 25 said eyelet during entry by said pin, a pair of levers respectively carrying said pin and element, a travelling fulcrum block for said levers, an actuating shaft, and means carried by said shaft for shifting said fulcrum 30 block and for tilting said levers.

In testimony whereof, I have signed my name to this specification.

EDWARD B. ALLEN.
